UNITED STATES PATENT OFFICE

2,164,552

FLUID OPERATED VACUUM DEVICE

George O. Taylor, Cicero, Ill., assignor to The Lubrication Corporation, Chicago, Ill., a corporation of Delaware

Application August 7, 1937, Serial No. 157,901

6 Claims. (Cl. 230—95)

This invention relates to fluid operated vacuum devices and more particularly to vacuum cleaners operated by compressed air or the like.

One of the objects of the invention is to provide a fluid operated vacuum device which is extremely simple and inexpensive to construct and positive and reliable in operation.

Another object of the invention is to provide a fluid operated vacuum device in which a single member serves both to conduct operating fluid into the device and to control admission of the fluid.

Another object is to provide a fluid operated vacuum device for use with a standard valved air chuck in which the chuck valve serves as a control valve to control admission of operating fluid to the device.

Other objects and advantages of the invention including novel combinations and particular features will be apparent from the following description of the accompanying drawing in which the single figure is a central section of an air operated vacuum cleaner embodying the invention.

The illustrated cleaner comprises a conduit 10 of Venturi formation carrying at one end a cleaner nozzle 12 of any desired formation. A filter bag 14 of suitable construction may be secured to the opposite end of the conduit 10 to receive and retain dirt picked up by the nozzle 12.

Air under pressure is supplied to the conduit through a tube 16 slidably mounted transversely of the conduit and having therein an outlet orifice 18 facing away from the nozzle 12. One end of the tube 16 is closed and terminates in a head or button 20 to be engaged by an operator's thumb, a pin 22 carried by the conduit 10 being slidable in a bore in the head to prevent turning thereof and of the tube 16.

The opposite end of the tube is open, preferably being formed with a series of air admitting slots, and extends through a suitable air nipple 24. The nipple 24 is formed for sealing engagement with a conventional air chuck 26 and is provided with a clamp 28 to hold the chuck securely thereon. The chuck is provided with an inwardly opening check valve 30 normally held closed by air pressure and which is aligned with the tube 16 when the chuck is secured to the nipple.

The parts are shown in released position with the valve 30 closed and no air being admitted to the tube 16. To operate the cleaner, the button 20 is engaged to press the tube 16 down to open valve 30 and admit air to the tube 16 to flow out through the opening 18. Flow of air through this opening creates a partial vacuum in the nozzle

12 so that dirt will be picked up and carried into the bag 14. When the button 20 is released the valve 30 will again close.

While one embodiment of the invention has been illustrated and described in detail it will be understood that many other embodiments might be devised and it is not intended to limit the scope of the invention to the form shown or otherwise than by the terms of the appended claims.

What is claimed is:

1. A fluid operated vacuum device comprising a conduit, a tubular member extending transversely of said conduit and slidably relatively thereto and formed with a transverse outlet opening within the conduit, and means including a valve secured to said conduit for supplying fluid to said tubular member said valve being disposed in the path of said tubular member to be operated by sliding movement thereof.

2. A fluid operated vacuum device comprising a conduit having an inlet at one end, a tubular member extending transversely across said conduit and slidably relative thereto and having an air outlet orifice facing away from said inlet, and means including a valve exterior to said conduit for supplying fluid to said tubular member, said valve arranged to be operated by sliding of the member.

3. A fluid operated vacuum device comprising a conduit having an inlet at one end, a tubular member extending transversely across said conduit and slidably relative thereto and having an air outlet orifice facing away from said inlet, means for preventing rotation of said tubular member, and means including a valve exterior to said conduit for supplying fluid to said tubular member, said valve arranged to be operated by sliding of the member.

4. An air operated vacuum device comprising a conduit having an air inlet at one end, a tubular member slidably mounted transversely of the conduit and extending completely thereacross, one end of said member being closed and the other end being open and there being an outlet opening intermediate the ends of said member within the conduit, means including a valve exterior to the conduit for supplying fluid to the tubular member, the open end of said member being adapted to operate the valve to control admission of air to the member.

5. In combination with an air chuck having a valve therein, a vacuum conduit, a nipple carried by said conduit for sealing engagement with the air chuck, a tube slidably transversely of the conduit and extending through said nipple, said

tube having an air outlet opening intermediate its ends within said conduit and one end of said tube engaging said valve to control it.

6. In combination with an air chuck having a valve therein, a vacuum conduit, a nipple carried by said conduit for sealing engagement with the air chuck, means for clamping the air chuck to

said nipple, a tube slidably carried by the conduit transversely thereof with one end extending through the nipple, said one end being engageable with said valve to open it, and said tube being formed with an air outlet opening within the 5 conduit.

GEORGE O. TAYLOR.
